CLAIM

The ornamental design for a nozzle attachment for a vacuum cleaner, as shown and described.

DESCRIPTION

FIG. 1 is a top, front view of a nozzle attachment for a vacuum cleaner showing our new design;

FIG. 2 is a top view thereof;

FIG. 3 is a front view thereof;

FIG. 4 is a right-side view thereof; and,

FIG. 5 is a perspective view thereof; attached to a vacuum cleaner shown in broken lines which forms no part of the claimed design.

The broken lines in FIGS. 1-5 depict elements of the nozzle attachment for a vacuum cleaner that form no part of the claimed design.
